(57) **CLAIM**

The ornamental design for a holder for coasters, as shown and described.

DESCRIPTION

FIG. 1 is a perspective view of a holder for coasters showing my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a left side elevational view thereof;

FIG. 7 is a right side elevational view thereof; and,

FIG. 8 is an environmental perspective view of the holder for coasters in an in-use configuration.

The broken lines FIG. 8 depict environment that form no part of the claimed design. The other broken lines in the drawings depict portions of the holder for coasters that form no part of the claimed design.

1 Claim, 8 Drawing Sheets
